UNITED STATES PATENT OFFICE.

THOMAS DAVISON, OF BRANTFORD, ONTARIO, CANADA.

RAIL-ANCHOR.

1,136,777.

Specification of Letters Patent. Patented Apr. 20, 1915.

Application filed November 19, 1914. Serial No. 873,078.

To all whom it may concern:

Be it known that I, THOMAS DAVISON, a subject of the King of Great Britain, and resident of Brantford, in the Province of Ontario, Dominion of Canada, have invented certain new and useful Improvements in Rail-Anchors, of which the following is the specification.

This invention relates to improvements in rail anchors, and the objects of the invention are to provide a simple and effective form of device which may be clamped to rails having different sized bases and will bear a uniform pressure against the ties to prevent slipping of the rails with respect thereto, and it consists essentially of the improved construction hereinafter described in detail in the accompanying specification and drawing.

20 In the drawing, Figure 1 is a perspective view of the invention in position on the rail. Fig. 2 is a sectional elevation. Fig. 3 is a perspective view of the bottom clamping member. Fig. 4 is a perspective view of the side clamping member. Fig. 5 is a perspective view of the clamping wedge.

In the drawings like characters of reference indicate corresponding parts in all the figures.

30 Referring to the drawings, A represents a rail and B the tie.

C represents the bottom clamping member including a portion 10 adapted to extend beneath the rail and a hook shaped portion 11 adapted to fit around the bottom flange of the rail as shown and formed with peripheral strengthening ribs 12.

14 represents an abutment flange formed on the bottom member and adapted to abut the side of the tie, strengthened with a transverse rib 15. The end of the bottom clamping member remote from the hook shaped portion 11 is formed with an abutment flange 16 and a transverse recessed portion 17 adapted to receive the clamping wedge D.

The end clamping member E is of the form shown in Fig. 4 and is adapted to fit over the end of the member C and is formed with a recess 18 into which the end of the member C is adapted to extend, the member E being of substantially U-shape and adapted to fit around the end of the member C and being formed with sides 19 having slots 20 through which the wedge D is adapted to extend. The member E is further formed

with an abutment flange 22 adapted to engage with the side of the tie B and is reinforced with a rib 23.

The wedge D is formed with a recess 24 adapted to engage the side 20. When driven a sufficient distance the upper side of the member E may be reinforced with ribs 25.

The member E when placed in position on the member C is adapted to engage the flange of the rails, the said flange fitting in the mouth 30 on the member E. The end of the member C extends through a throat in the recess 18 against the rear wall of the member E.

In use the bottom clamping member C is placed on the rail adjacent to the tie. The member E is fitted over the end and the wedge D driven in, connecting the two members. When the wedge has been driven in a sufficient distance the side 20 will catch in the recess 24. The wedge D may be removed by a blow from a sledge in the reverse direction.

It will be seen that by using different sizes of wedges the device may be attached to rails having different sized bases.

As many changes could be made in the above construction and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

1. A rail anchor comprising a bottom member formed on one end with a hook shaped portion adapted to embrace the flange of the rail and being formed on the opposite side with an abutment flange, an end clamping member adapted to fit over the bottom clamping member having a portion adapted to embrace the side of the bottom flange of the rail, having slots to receive a wedge and being formed on the underside with an abutment flange adapted to engage the side of the tie, a wedge adapted to extend through said slot and to bear against the abutment flange on the end of the bottom clamping member.

2. A rail anchor comprising a bottom clamping member formed on one end with a hook shaped portion adapted to embrace the side of the rail, said hook shaped portion having peripheral reinforcing flanges

and being formed on one end with an abutment flange and on the bottom with an abutment flange having a reinforcing rib, an end clamping member fitting over the end of the bottom clamping member formed with a portion adapted to embrace the end of the rail, formed with slots to receive a wedge and formed on the underside with an abutment flange having a reinforcing

rib, and a wedge adapted to extend through 10 the said slot and formed with a recess in which a portion of the end clamping member is adapted to engage.

THOMAS DAVISON.
